HOLDOVER TANK FOR AIR
CONDITIONERSFred M. Young, Racine, Wis., assignor to Young
Radiator Company, Racine, Wis.

Application April 8, 1935, Serial No. 15,239

6 Claims. (Cl. 257—240)

This invention relates to improvements in devices commonly used on railway coaches wherein a refrigerator plant is used in connection with an air cooling and conditioning unit and has for its object continuing the operation of the air cooling and conditioning device during the time the compressor is not in operation, as for example, when the train is stopped at stations or otherwise detained temporarily.

10 Applicant's device pertains particularly to the type of installation wherein the air circulating and cooling device and the compressor and condenser are for convenience, made in separate units and wherein the pre-cooled solution in the hold-over tank is circulated when the refrigerator system is not in operation, the pre-cooled solution in the holdover tank then being circulated through a special air cooling coil which is positioned adjacent the air cooling evaporator, where-by the circulated air may be cooled continuously. The pre-cooled solution will be re-cooled by the natural accumulation of ice on the tank coils, this ice having accumulated during the time the compressor was in operation.

25 The object of this invention is to provide a simple, strong, efficient and durable holdover tank unit having preferably two separate cores and a tank header bound together into a single unit whereby this unit may be easily placed in position 30 in the tank and the entire assembly substantially held together.

I accomplish these objects by providing side bars which interconnect the removable header and the tube plates and further by forming the 35 enclosing tank in two horizontal trough shaped members each having preferably narrow inturned edges which are welded together to thereby form a shell with inwardly extending longitudinal ribs, thus providing supporting means for the inter-connecting bars on the core unit, whereby the core assembly may be inserted into the tank and withdrawn drawer like.

40 A further object of this invention is to provide means whereby the liquid level in the tank may be conveniently observed. Obviously applicant's device may be designed to make use of other types of cores than are shown, some of which may be adapted for either heating or cooling purposes. It will be understood that in the form shown of 45 the invention, the coils are used as evaporators which are operated simultaneously with the air cooling evaporator coils but preferably under separate manual control.

To these and other useful ends this invention 50 consists in matter hereinafter set forth and

claimed and shown in the accompanying drawing in which:

Figure 1 is a side elevation of the core unit, showing the tank in section on line 1—1 of Figure 3, a portion of two tubes being removed to disclose the spray tube.

Figure 2 is a front sectional elevation of the unit shown in Figure 1, taken on line 2—2 of Figure 1.

Figure 3 is a rear sectional elevation of the unit taken on line 3—3 of Figure 4.

Figure 4 is a side elevation of the complete device.

Figure 5 is an enlarged front view of the glass window showing a fraction of the rear head of the tank.

Figure 6 is a transverse section of the glass window showing a fraction of the rear head of the tank taken on line 6—6 of Figure 5.

Figure 7 is a sectional view of the core header 30, taken on line 1—1 of Figure 2.

Thus I have shown the preferred form of my invention, wherein reference character A is used to designate the upper core and B the lower core in their entirety. Reference numeral 10, designates the upper half of the tank and numeral 11, designates the lower half of the tank less the end members. The tank members are formed from separate plates and are each provided with inwardly projecting flanges 12 and 13 respectively. After these halves are formed in the shape clearly shown in Figures 2 and 3, they are preferably arc welded together as at 14. The rear end of the thus formed shell preferably embraces the head 16, as clearly shown in Figure 1, and to which it is preferably arc welded as at 17. This head 16, is supplied with a suitably positioned glass window comprising a ring 18 which is preferably arc welded to the head as at 19. Ring 18 is provided with a flange seat 20. A glass disk 21, having a gasket 22 on each side thereof, fits loosely in the recess over flange 20 and a ring 23 is formed to register with the ring 18 and the outside gasket 22 and is adapted to seal the assembly by means of cap screws 24. The level and condition of the liquid coolant in the tank may be noted through the glass 21 from time to time. The front end of the tank is provided with an outwardly projecting flange 25 to which the front head is attached as will hereinafter appear. Thus I have shown my preferred form of tank and observation window.

I shall now describe the preferred form of my improved core assembly. Coils A and B, it will be noted, are each formed into two series multi-

ple paths for the passage of the refrigerant. For example, coils A are provided with an inlet header 38 and an outlet header 31 (see Figure 2). The refrigerant enters through pipe 29 and will pass through the coils as illustrated by arrows, back and forth sinuously until the header 31 is reached from whence the refrigerant or gas may return to the compressor through pipe outlet 32.

Refrigerant will also pass into coil B by means of inlet pipe 33 and header 35 and pass through the two tube series as indicated by arrows, passing out at header 36 through outlet pipe 37. Obviously these two multiple circuits may be supplied individually direct from the condenser or elsewhere, the preferred plan being to supply regulating valves on inlet pipes 29 and 33 having suitable connections to the condenser, thus providing manual controlling means.

It will be noted by scrutinizing Figures 2 and 3, that the tank is well filled with tubes which are staggered vertically or in direction of tank liquid flow, except that a space 40 is provided above header 30. In this space 40 I suitably position a tube 41 having an end cap 42. Suitably positioned, spaced apart orifices are provided in tube 41 whereby the incoming liquid will be sprayed over the tubes which are above the level of the solution in the tank. Or if all of the tubes are below the solution level, the incoming solution will be equally distributed into the tank. The liquid outlet from the tank is designated by reference character 43. This outlet is connected to the suction of a liquid pump (not shown). This pump is adapted to force the liquid from the tank through a supplemental cooling coil (not shown) and back into the tank through the orifices in pipe 41.

I shall now describe my improved means for making a single unit of the tubes, tube plates 40 and tank head and the manner of supporting them in the tank. The ends of the tubes are expanded as at 60 and loops 61 are adapted to connect certain tube ends as illustrated and for the purpose already outlined. Two tube plates 45 62-62 are provided having openings through which the expanded ends 60 extend and are bonded thereto.

In order to increase the efficiency of the device, I supply closely spaced fins 63, having flanged openings through which the tubes extend in the usual manner.

The tube plates are preferably cut away midway their sides as at 64. These cut away portions are adapted to receive angle bars 65-65 as indicated. Each plate is welded to the bars at their contact points and the spaces 64 are of a proper width to provide free room for the tank ribs 12 and 13. The front end of the angle bars 65 project slightly past the return bends 60 61 and these ends are suitably welded or attached to the tank head 66 as at 67. Means may also be provided for further securing the tube plates on their upper and lower sides to the head 66, thus to more firmly bind the head to the cores and make a strong unitary assembly. It will also be noted that pipe 41 extends through openings in the head and the tube plates. This pipe is seal welded to the head 66, and may also be welded to the tube plates thus to further strengthen the assembly. The inlet and outlet pipes to the coil headers are also welded to the tank head 66.

Thus it will be seen that bars 65 are positioned thereby to support the core unit in a central position in the tank and hold the head 66 so

it registers with the tank flange 25. I provide bolts 10 whereby when a suitable gasket is positioned on the tank flange, these bolts may be drawn up tight and the tank made liquid or gas proof.

Clearly the core unit may be easily moved in and out of the tank, drawer like. Thus the assembly will be suitable for rough handling and will be protected against the possibility of the core working loose and being damaged.

Clearly applicant's principal object is to provide a novel tank and novel means for closing the open end of the tank and to provide a core assembly preferably attached to the removable tank head, whereby the core is adequately supported and the head and core together may be removed and replaced drawer like. Obviously the edges of one trough only may be turned inwardly. It will also be understood that for some uses the core need not be attached to the head 20 and that the pipes may be extended through the permanent tank head.

In devices of the class it is customary to provide a bundle of tubes in the tank in which a portion or all of the refrigerant may be expanded, the tank being well filled with a liquid consisting of preferably a mixture of water and prestone. Thus the solution is freeze proof against normal exterior weather temperatures. However the action of the refrigerant in the tubes 30 will first chill the solution in the tank and then ice will form on the outside walls of the tubes. When the refrigerator plant has been stopped, as at railway stations, thus discontinuing the flow of refrigerant to the tank and the evaporator coils used for cooling the air, the solution in the tank may then be circulated through a supplemental cooling coil through which the circulated air passes after leaving the evaporator coil which is now inactive. Thus the tank solution will pass through the tank and the auxiliary air cooling coil and cool the passing air as long as the ice on the coils and the reduced temperature of the solution answers the purpose, the tank and coils therein being of a capacity 45 to properly cool the air for normal stopovers. When the compressor is again started, enough refrigerant may be caused to pass through the tank cores to again prepare for another stopover.

I provide an air vent for the tank, comprising a chamber, or dome 71 and a loop pipe 72. Pipe 72 being connected to the top of the dome. Small openings are provided in the tank which register with the dome and in order to supply means 55 for draining back any liquid that may pass into the dome, I provide a tube 73. This drain tube preferably extends to a point where it will be below the liquid level. Thus any accumulation of liquid may return to the tank undisturbed 60 and dry air pass into or from the tank.

Having thus shown and described my invention, I claim:

1. A device of the class described, comprising a tank made from two longitudinal halves having 65 adjacent edges turned inwardly and being suitably joined together forming a shell, a head for one end of said shell, the other end having an outwardly extending flange, a head for said other end which registers with said flange means for 70 removably binding and sealing said head to said flange, a bundle of tubes fitting loosely in said tank and having spaced apart tube plates through which the tubes of said bundle extend, means attached to opposite sides of said tube plates and 75

to said last mentioned head whereby said means will rest on said inwardly turned edges to thereby position and support said head and tube bundle.

5 2. A device of the class described, comprising a tank made from two longitudinal halves having adjacent edges turned inwardly and being suitably joined together forming a shell, a head for one end of said shell, the other end having an outwardly extending flange, a head for said other end which registers with said flange means for removably binding and sealing said head to said flange, a bundle of tubes fitting loosely in said tank and having spaced apart tube plates 10 through which the tubes of said bundle extend, means attached to opposite sides of said tube plates and to said last mentioned head whereby said means will rest on said inwardly turned edges to thereby position and support said head and tube bundle. an inlet pipe extending over said tubes having a number of spaced apart outlets and extending through said last named head, an outlet connection in the bottom of said tank, inlet and outlet connections from said tubes extending through said last named head.

15 3. A device of the class described, comprising a tank made from two longitudinal troughs having adjacent edges turned inwardly and being joined together forming a shell, a head for one end of said shell, the other end having an outwardly extending flange, a head for said other end which registers with said flange, means for removably binding and sealing said head to said flange, instrumentalities rigidly attached to said last named head having members adapted to register with said inwardly turned flange to thereby position and support said last named head and instrumentalities and whereby said last named head may be removed and replaced drawer like.

20 4. A device of the class described, comprising a tank made from two longitudinal troughs, one

of said troughs having its edges turned inwardly and being joined to the edges of the other trough forming a shell, a head for one end of said shell, the other end having an outwardly extending flange, a head for said other end, means for removably 5 binding and sealing said last named head to said flange, instrumentalities rigidly attached to said last named head having members adapted to register with said inwardly turned edges to thereby position and support said head and instrumentalities and whereby said instrumentalities and head may be removed and replaced drawer like.

10 5. A device of the class described, comprising a tank made from two longitudinal troughs having adjacent edges turned inwardly and being joined together forming a shell, a head for one end of said shell, the other end having an outwardly extending flange, a head for said other end which registers with said flange, means for 15 removably binding and sealing said head to said flange, instrumentalities rigidly attached to said last mentioned head having members adapted to register with said inwardly turned edges to thereby position and support said instrumentalities and head may be removed and replaced drawer like, a window in said first mentioned head and means to removably bind and seal said window thereto.

20 6. A device of the class described, comprising a tank made from two longitudinal troughs having adjacent edges turned inwardly and joined together to form a shell, a head for one end of said shell, the other end having an outwardly extending flange, a head for said other end, means to 25 removably bind and seal said head to said flange, instrumentalities attached to said last named head and supported on said inwardly turned flanges whereby said instrumentalities and head may be removed and replaced drawer like. 40

FRED M. YOUNG.
